Patented Jan. 5, 1915.

UNITED STATES PATENT OFFICE.

LEE B. LESLIE AND MAX E. FEUERBACHER, OF DALLAS, TEXAS; SAID FEUERBACHER
ASSIGNOR TO SAID LESLIE.

GARDEN-HOSE HOLDER.

1,123,900.

Specification of Letters Patent.

Patented Jan. 5, 1915.

Application filed June 16, 1914. Serial No. 845,380.

To all whom it may concern:

Be it known that we, LEE B. LESLIE and MAX E. FEUERBACHER, citizens of the United States, residing at Dallas, in the county of Dallas and State of Texas, have invented certain new and useful Improvements in Garden-Hose Holders, of which the following is a specification.

Our invention relates to a new and useful garden hose holder, and its object is to provide a device that will support the nozzle or discharge end of a garden hose, holding the same adjustable at various heights, and making the stream of water adjustable in a direction either in a horizontal or vertical plane.

A further object of the invention is to provide a device of the character described, that will be strong, durable, simple and efficient and comparatively easy to construct.

With these and various other objects in view, our invention has relation to certain novel features of the construction and use, an example of which is described in the following specification and is illustrated in the accompanying drawing, wherein:

Figure 1 is a view showing our complete device in side elevation. Fig. 2 is a front view of the same. Fig. 3 is a detail sectional view, the section being taken upon the line $x-x$ of Fig. 2. Fig. 4 is a horizontal sectional view taken upon the line $y-y'$ of Fig. 1.

Referring now more particularly to the drawing, wherein like reference characters designate similar parts in all the figures, the numeral 1 denotes a vertical rod or pipe, which has its lower end threaded to enter a socket formed in the top of a sharp pointed spike 2. From the upper end of the spike 2 a spur 3 projects laterally a short distance and terminates in a downwardly turned sharp pointed extremity. The upper portion of the member 1 is passed through a eye 4 of an eye-bolt 5, the threaded portion of which projects horizontally from the member 1. Upon the bolt 5 are carried two collars 6 and 7 which are clamped against each other and against the member 1 by a wing-nut 8. The collar 6 comprises two portions A and B, the former being rectangular and the latter cylindrical. The portion A of the member 6 is formed with a vertical V-shaped handle 9, the wall of which bears against the member 1 when the

wing-nut 8 is screwed tight against the member 7. The portion A of the member 6 is furthermore formed with a horizontally elongated recess 10 within which a portion of the eye 4 is recessed. Thus it is seen that the member 6 is restricted against rotation about either a horizontal axis established by the bolt 5 or the vertical axis established by the member 1.

The member 7 is semi-cylindrical at its bottom and rectangular at its top, its upper portion being somewhat enlarged as indicated at 12. The portion 12 of the member 7 is formed with a channel 13 extending transversely of the bolt 5 and within this channel there is secured by means of a screw 14 a spring clip 15 open at its top and comprising a pair of arcuate upwardly projecting members between which the nozzle or discharge end of a hose may be engaged as indicated at 15.

When the nut-wing 8 is screwed tight against the member 7, the parts 1, 6 and 7 are maintained in a fixed relation. When the nut-wing 8 is loosened, all of the parts 4 to 16 inclusive may be vertically adjusted relative to the rod 1. Also the wing nut 8 being loose, it is possible to swing said part about the vertical axis established by the bolt 5. Thus it is apparent that by means of our hose holder, a stream of water may be directed from the hose in any desired direction and at any angle relative to the ground.

The invention is presented as including all such modifications and changes as properly come within the scope of the following claims.

What we claim is:

1. In a device of the character described, the combination with an elongated vertical supporting member, of an eye-bolt projecting horizontally from said member, said member being passed through the eye of said bolt, a pair of collars mounted upon the eye-bolt, one of which is adjacent to the vertical member and is formed with a groove receiving said member and with a recess receiving a portion of the eye of the bolt, a clamping nut adapted to engage the two collars in a rigid relation with the vertical member and bolt, and a spring clip rigidly secured to the collar farthest removed from the vertical member and adapted to engage a nozzle or hose.

2. In a device of the character described,

the combination with a vertically elongated member, of an eye bolt projecting horizontally from said member, said member being passed through the eye of said bolt, a clamping nut mounted upon the outer end portion of the bolt, a pair of collars disposed between said clamping nut and the vertical member and adapted to be clamped by said nut in a rigid relation with the vertical member and bolt, the collar nearest adjacent to the vertical member being restricted from rotation about the axis established by the vertical member and by the bolt, and a

spring clip rigidly secured to the member nearest adjacent to the clamping nut said clip being formed to engage a nozzle or hose.

In testimony whereof we have signed our names to this specification in the presence of two subscribing witnesses.

LEE B. LESLIE.

MAX E. FEUERBACHER.
